RAIL JOINT

Frank G. Gorick, Pittsburgh, Pa., assignor of three-tenths to Joseph D. Ripp and three-tenths to Harry B. Salkovitz, Pittsburgh, Pa.

Application July 1, 1938, Serial No. 216,905

5 Claims. (CL. 238—205)

This invention relates to rail joints for connecting the ends of railroad rails together.

One of the primary objects of the invention is to provide a rail joint which does not use bolts and nuts extending through the rails, so as to eliminate the necessity of drilling holes through the rail terminals and thereby weakening the same.

Another object of the invention is to provide a rail joint which positively prevents creeping or separation of the rail ends caused by vibration transmitted to the rails from passing trains.

Still another object of the invention is to provide a rail joint by means of which defective rails may be quickly replaced.

Yet another object of the invention is to provide a rail joint which provides a simple and effective device that may be easily and rapidly applied to secure the ends of the rails to one another, and enabling the joining of the rails in an expeditious manner thereby eliminating interference with traffic, while changes to the track are made.

Further objects of the invention are to provide a rail joint which is comparatively simple in its construction and arrangement, strong, durable and efficient in its use, conveniently secured in position and inexpensive to manufacture.

To the accomplishment of these and such other objects as may hereinafter appear, the invention consists of the novel construction, combination and arrangement of parts specifically described and illustrated in the accompanying drawing, wherein is shown an embodiment of the invention, but it is to be understood that changes, variations and modifications can be resorted to which come within the scope of the claims hereunto appended.

In the drawing, forming part of this specification in which the same reference characters designate corresponding parts throughout the several views:

Figure 1 is an isometric view, showing the invention in connection with the adjacent ends of two rails.

Figure 2 is a fragmentary top plan view, showing one of the cams including the springs which locks the cam in position.

Figure 3 is a transverse sectional view along lines 3—3 in Figure 2.

Figure 4 is a side view of one of the cams as used in the invention.

Figure 5 is an end view of Figure 4.

Figure 6 is a perspective view of one of the holding down springs as used in the invention.

Figure 7 is a perspective view of the lock spring as used in the invention.

Referring more in detail to the drawing, 10 and 11 designate respectively the rails of a joint. 12 is the joint-plate or chair, preferably constructed in a single piece having a base-plate 13 and inwardly extending flanges 14 formed on the side edges thereof which are adapted to engage over the base-flanges 15 of said rail sections 10 and 11. In addition to said base flanges 15 the 10 said rail section includes the head 16 and the web 17. The inner contour of said flanges 14 are shaped, so as to conform to the configuration of the base flanges 15.

The aforesaid flanges 14 extend the entire 15 length of the base-plate 13 and are provided with upwardly directed extensions 18, thereby engaging the web 17 of the rails.

If desired, these extensions 18 may reach the lower edges 19 of the head 16 of the rails 10 20 and 11 and form means for providing an additional support for said heads 16 of the rails.

The base-plate 13 of chair 12 is provided with outwardly extending slotted lugs 20 adapted for the reception of spikes (not shown) for securing 25 said chair 12 to the usual railroad ties (not shown).

To prevent movement of the rails 10 and 11 in the chair 12, the rails are locked to the chair by means of cams 21, detailed in Figures 4 and 5. 30 The present invention shows four of said cams arranged, one in each corner of the chair, but of course if so desired, only two cams, arranged at diagonally opposite corners may be used.

As clearly shown in Figures 2 and 3, said cam 21 is hingedly supported on a stub-shaft 22, one end 23 of which is secured in the upwardly extending elongated lug 24 at the top of flange 14 and the other end 25 is similarly secured in the upwardly directed extension 18 of chair 12. In 40 parallel alignment with said elongated lug 24 is an elongated slot 26 through which the cam penetrates.

The cam 21, as used in this invention, is shown detailed in Figures 4 and 5 and consists of a flat 45 steel member having a curved cam-like portion 27 which terminates at one end into a lever 28 by means of which the cam may be manipulated when in assembled position, that is, when the roughened or serrated curved cam 27 frictionally 50 engages the upper face 29 of the rail base flange 15. Of course, the cam turns on an offset bore 30. The serrated cam portion 27 is preferably biased, as indicated by the numeral 31, so as to conform to the usual taper of the base flange of 55

the rail and to facilitate a positive grip when the cam is tightened against the rail.

In order to prevent the cam 21 from opening up when in clamped position I use a flat spring 32, the free end 33 of which presses against the upper edge 34 of said cam-lever 28, and another short flat spring 35 lies on top of said first mentioned spring 32 in a manner as best shown in Figure 1. Both springs are held securely in position by means of a screw and lockwasher.

From the foregoing description the use and operation of the improved invention will be readily understood and it will be noticed that bolts, nuts and locknuts are entirely dispensed with thus eliminating the necessity of drilling holes through the rail terminals thereby considerably weakening the same.

In practice, I have found the design of my invention illustrated in the accompanying drawing and referred to in the above description, as the preferred embodiment, is the most efficient and practical; yet realizing the conditions concurrent with the adoption of the device will necessarily vary, I therefore desire to emphasize that various minor changes in details of construction, proportion and arrangement of parts may be resorted to, when required without sacrificing any of the advantages of the invention as set forth.

I claim:

1. In a device of the class described comprising a one piece rail-chair adapted to receive the adjacent ends of the rail sections, said rail-chair arranged to conform to the contour of the base-flange and web of said rail sections and including a base-plate having inwardly extending flanges and upwardly directed extensions, the ends of said inwardly extending flanges provided with elongated openings, an upstanding lug along each side of said openings adapted to pivotally support a cam which securely grips the top portion of the base-flange of said rail sections.

2. In a device of the class described comprising a one piece rail-chair adapted to receive the adjacent ends of the rail sections, said rail-chair arranged to conform to the contour of the base-flange and web of said rail sections and including a base-plate having inwardly extending flanges and upwardly directed extensions, the ends of said inwardly extending flanges provided with elongated openings, an upstanding lug along each side of said openings adapted to pivotally support a cam which securely grips the top portion of the base-flange of said rail sections, said cam provided at the exposed portion with a lever-like extension which comes, when said cam is tightened against the base-flange of said rail section, in parallel alignment with said rail-chair.

3. In a device of the class described comprising

a one piece rail-chair adapted to receive the adjacent ends of the rail sections, said rail-chair arranged to conform to the contour of the base-flange and web of said rail sections and including a base-plate having inwardly extending flanges and upwardly directed extensions, the ends of said inwardly extending flanges provided with elongated openings, an upstanding lug along each side of said openings adapted to pivotally support a cam which securely grips the top portion of the base-flange of said rail sections, said cam provided at the exposed portion with a lever-like extension which comes, when said cam is tightened against the base-flange of said rail section, in parallel alignment with said rail chair and spring means to adjustably retain said cam in locked position.

4. In a device of the class described comprising a one-piece rail-chair adapted to receive the adjacent ends of the rail sections, said rail-chair arranged to conform to the contour of the base-flange and web of said rail sections and including a base-plate having inwardly extending flanges and upwardly directed extensions, the ends of said inwardly extending flanges provided with elongated openings, a cam pivotally mounted penetrating said elongated opening and adapted to securely clinch the rail section, said cam provided at the exposed portion with a lever-like extension which comes, when said cam is tightened against said rail section, in parallel alignment with said rail-chair, spring means to adjustably retain said cam in locked position, said spring means comprising a flat spring adapted to exert pressure to the free end of said lever-like extension of said cam.

5. In a device of the class described comprising a rail-chair adapted to receive the adjacent ends of the rail sections, said rail-chair arranged to conform to the contour of the base-flange and web of said rail sections and including a base-plate having inwardly extending flanges and upwardly directed extensions, the ends of said inwardly extending flanges provided with elongated openings, a cam pivotally mounted penetrating said opening and adapted to clinch the rail section, said cam provided at the exposed portion with a lever-like extension which comes, when said cam is tightened against said rail section, in parallel alignment with said rail-chair, spring means to adjustably retain said cam in locked position, said spring means comprising a flat spring exerting pressure against the free end of said lever-like extension of said cam and another flat spring locking said first mentioned flat
